UNITED STATES PATENT OFFICE

102,671

DESIGN FOR A BOTTLE CARRIER

Everett Worthington, Chicago, Ill., assignor to The Coca-Cola Company, Wilmington, Del., a corporation of Delaware

Application May 22, 1936, Serial No. 62,769

Term of patent 14 years

To all whom it may concern:

Be it known that I, Everett Worthington, a citizen of the United States and resident of Chicago, Cook County, Illinois, have invented a new, original, and ornamental Design for Bottle Carriers, of which the following is a specification, reference being had to the accompanying drawing forming part thereof.

Fig. 1 is a front view of the bottle carrier,

showing my new design;

Fig. 2 is an end view;

Fig. 3 is a rear view; and

Fig. 4 is a top plan view thereof.

I claim:

The ornamental design for a bottle carrier as shown.

EVERETT WORTHINGTON.
